US0D1049927S

(12) **United States Design Patent** (10) Patent No.: **US D1,049,927 S**
(45) Date of Patent: ** Nov. 5, 2024

(54) **AUTOMOBILE**

(71) Applicant: **CIRCLE**, Paris (FR)

(72) Inventor: **Alain Di Duca**, Paris (FR)

(**) Term: **15 Years**

(21) Appl. No.: **35/518,176**

(22) Filed: **Jul. 25, 2023**

(80) **Hague Agreement Data**

Int. Filing Date: **Jul. 25, 2023**

Int. Reg. No.: **DM/230927**

Int. Reg. Date: **Jul. 25, 2023**

Int. Reg. Pub. Date: **Aug. 25, 2023**

(30) **Foreign Application Priority Data**

Feb. 17, 2023 (EM) 015011936-0001

(51) LOC (14) Cl. **12-08**

(52) U.S. Cl.

USPC **D12/90**
